UNITED STATES PATENT OFFICE.

JOHN B. CLERMONT, OF NEW YORK, N. Y., ASSIGNOR TO S AND S WINDOW CORPORATION,
OF NEW YORK, N. Y., A CORPORATION OF NEW YORK.

PULLEY-CASE.

1,132,651.

Specification of Letters Patent. Patented Mar. 23, 1915.

Application filed September 30, 1914. Serial No. 364,229.

To all whom it may concern:

Be it known that I, JOHN B. CLERMONT, a citizen of the United States, and a resident of the borough and county of the Bronx, 5 city and State of New York, have invented a certain new and useful Improvement in Pulley-Cases, of which the following is a specification.

My invention relates to pulley cases and 10 has for its object to provide a case which consists of a single piece of material bent to the desired shape to form a rigid, durable support adapted to accommodate single, double or other pulleys and which is particularly adapted for use in connection with 15 windows of the type commonly known as double hung windows.

Other objects of my improvement will appear from the description hereinafter and 20 the features of novelty will be pointed out in the appended claims.

Reference is to be had to the accompanying drawings which illustrate an example of my improvement and in which—

25 Figure 1 represents the blank from which the case is constructed; Fig. 2 is a side elevation of the finished case with the pulley in position therein; Fig. 3 is a plan view thereof and Fig. 4 is an end elevation.

30 As shown in Fig. 1 the blank comprises two main sections 5 and 6 which converge toward and are connected with a relatively narrow intermediate section 7. The main sections 5 and 6 are continued transversely 35 in opposite directions to form auxiliary sections 8 and 9 each of which in turn is prolonged lengthwise to form projecting sections 10 and 10^a. The main sections 5 and 6 at the edges opposite to those at which the 40 sections 8 and 9 are located are provided with projections 11 and 12 adapted in the finished case to fit into recesses 13 and 14 formed in the free edges of the sections 8 and 9. The blank may be constructed of 45 metal or other suitable material and may be stamped or produced in any other desired manner. Before being formed into the finished case the main sections 5 and 6 are preferably provided with apertures 15 50 adapted to register and receive the axle of the pulley while the projecting sections 10 and 10^a are similarly provided with openings 16 for the accommodation of screws or other fastening devices.

In forming the case the main sections 5 and 6 are bent at right angles to the intermediate section 7 along the lines 17 to form the opposite side walls of the case, the section 7 forming the top thereof as shown in Figs. 3 and 4. The auxiliary sections 8 and 9 in the example shown are now bent in opposite directions along the lines 18 until they extend at right angles to the main sections 5 and 6 in which condition the free edge of each section 8 and 9 will lie against an edge of the opposite sections 5 and 6 and the projections 11 and 12 will be located respectively in the recesses 13 and 14. The said sections 8 and 9 thus form the end walls of the case it being understood that the projections 11 and 12 may if desired be of sufficient length to permit the ends thereof to be bent over upon the sections 8 and 9 for the purpose of securing the side walls 5 and 6 and end walls 8 and 9 firmly together. 75 At this stage the projecting sections 10 and 10^a are bent along the lines 19 so as to extend outwardly from the end walls 8 and 9 at any desired angle thereto to form attaching lugs, the illustrated form showing said lugs extending horizontally at right angles to said end walls. In this condition the apertures 15 are in axial alinement so that the pulley 20 may be placed in position in the case and the axle 21 thereof inserted 85 through said apertures and the axial opening of the pulley and the ends of said axle riveted or otherwise secured in the side walls 5 and 6. In this manner the pulley 20 is rotatably supported in the case while the 90 axle 21 provides an additional securing means for maintaining the case in its operative condition against any strains to which the pulley 20 or the case may be subjected.

It will be seen that the completed case is 95 open at opposite corners and at the bottom so that it may be readily utilized to support the pulley in position to accommodate cords or the like extending vertically, horizontally or at any angle intermediate thereto, 100 the lugs 8 and 9 serving as a means for securely attaching said case to a supporting means in each instance. The openings at the corners of the case also permit access to the cords or the like and make it unnecessary to detach the case if such access is desired for any purpose. At the same time the dead weight of the case is reduced to a 105

minimum without in any way impairing its strength. By properly proportioning the section 7 and the sections 8 and 9 the case may be made of any desired width adapted to properly accommodate pulleys having single, double or more grooves, or one, two or more separate pulleys if desired.

My improved case is extremely simple in construction, comprises no complicated lines necessitating intricate apparatus to produce and is of maximum serviceability and easy to attach and detach as may be found necessary.

My improved case in all of its forms occupies a minimum of space and is thus particularly adapted for use in places of small dimensions.

It will of course be understood that the auxiliary sections 8 and 9 may both be formed integral with the same main section 5 or 6 instead of as shown in which case both sections 8 and 9 would be bent in the same direction into engagement with the other main section when forming the pulley case. It will also be apparent that the locations of the projections 11 and 12 and the recesses 13 and 14 may be reversed if desired and further that in some instances these elements may be omitted entirely.

Various changes in the specific form shown and described may be made within

the scope of the claims without departing from the spirit of my invention.

I claim:

1. A blank for a pulley case comprising an intermediate section, main sections extending therefrom in opposite directions, auxiliary sections extending from said main sections in a direction transverse to the length of the blank and projecting sections forming continuations of said auxiliary sections in opposite directions.

2. A blank for a pulley case comprising an intermediate section, main sections extending in opposite directions therefrom, 45 projections extending outwardly from opposite edges of said main sections, auxiliary sections extending from opposite edges of said main sections in directions transverse to the length of the blank and provided at 50 their outer edges with recesses adapted to receive said projections, and projecting sections forming continuations of said auxiliary sections in opposite directions parallel 55 to the length of the blank.

In testimony whereof I have hereunto set my hand in the presence of two subscribing witnesses.

JOHN B. CLERMONT.
